Esq.; Lombard Geliebter LLP

(57) **CLAIM**

The ornamental design for a drain outlet, as shown and described.

DESCRIPTION

FIG. 1 is a top perspective view of a drain outlet according to one embodiment of my new design;

FIG. 2 is a bottom perspective view of a drain outlet according to one embodiment of my new design;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a center cross sectional view taken from line 9-9 of FIG. 7;

FIG. 10 is a top perspective view of a drain outlet according to a second embodiment of my new design;

FIG. 11 is a bottom perspective view of a drain outlet according to a second embodiment of my new design;

FIG. 12 is a front view thereof;

FIG. 13 is a back view thereof;

FIG. 14 is a left side view thereof;

FIG. 15 is a right side view thereof;

FIG. 16 is a top view thereof;

FIG. 17 is a bottom view thereof; and,

FIG. 18 is a center cross sectional view taken from line 18-18 of FIG. 16.

The drain outlet is shown with a symbolic break in its length. The appearance of any portion of the article between the break lines forms no part of the claim.

The dashed lines shown in the drawings illustrate environmental structure and form no part of the claimed design.

1 Claim, 18 Drawing Sheets
